CONVERTIBLE CHAIR

Axel Lanquist, Chicago, Ill.

Application May 14, 1937, Serial No. 142,586

1 Claim. (Cl. 155—48)

This invention relates to improvements in convertible chairs.

One of the objects of this invention is to provide a chair which normally has a back and side arms and is of the general proportions of an easy chair and which may be unfolded to present a strong and serviceable bed.

Another object of this invention is to provide a convertible chair which is strong, compact and of economical construction.

A further object of this invention is to provide a convertible chair which provides within itself a storage compartment for the usual articles of bedding, and especially a mattress which may be used in conjunction therewith.

A further object relates to the novel construction of the back of my chair which may be unfolded to comprise the completed bed and which is supported by the chair base and unfolded arm rest.

Other objects relate to details of structure and arrangement of parts which will be apparent from a consideration of the following specification and drawings, wherein:

Fig. 1 is a side elevation of my improved convertible chair in its normally closed position.

Fig. 2 is a side elevational view showing the seat and arm portion of the chair unfolded forwardly so that it is horizontally aligned with the base of the chair, the seat being supported by the arm rests.

Fig. 3 is a side elevation showing a further step in the conversion of the chair into the bed wherein the back of the chair has been swung forwardly and downwardly onto the base.

Fig. 4 is a further development of Fig. 3 showing a nested portion of the back unfolded therefrom and resting on the unfolded arms which form a support therefor.

Fig. 5 is a longitudinal sectional view of my convertible chair taken on line 5—5 of Fig. 6.

Fig. 6 is a sectional view taken on line 6—6 of Fig. 5.

Fig. 7 is a plan view of my device when completely opened up into a bed.

Fig. 8 is a side sectional elevation thereof.

Referring more in detail to the drawings, 10 indicates the base of the chair supported at its forward end by legs 11 and at its backward end by legs 12. The forward legs 11 extend directly underneath the forward corners of the base and the rearward legs 12 extend preferably from lateral extensions 13, at the rearward corners of the chair. A pair of side arm rests 14 are provided, which may have a curvilinear contour

towards the forward end, or of any desired decorative shape. The portions of the arm which extend backwardly towards the sides 15 of the back of the chair, may be formed horizontally for a short distance, as at 16. The height of 15 the arm at the portion 16 from the upper edge of the arm to the bottom of the seat 17 is equal to the height of the base at said point above the floor level.

The side arm supports 14 may be constructed 10 of solid side walls, or may comprise a horizontal rail carried by vertical supports at each end. The seat may be formed of a solid surface, or it may be formed in a rectangular outline and carry a seat cushion or upholstering. Likewise 15 a cushion or upholstering may be provided on the chair back, the arrangement of the cushion in this instance, however, being such that when the chair is converted, as will be later set forth, this cushion will nest into the base 10. 20

The forward edge of the seat is provided with a hinge, as at 18, hinging it to the base 10 so that the arms and seat may be turned outwardly on a vertical plane until the portion 16 rests on the floor and forms a support for the 25 seat. The back of the chair, generally indicated at 15, is also hinged to the base at 19 adjacent the seat level 17, and after the arms have been completely unfolded the back may be turned in a vertical plane on its hinges until it rests on the 30 base portion 10 and partially on the unfolded seat as shown in Fig. 3. This back consists of two portions folded against each other as at 20 and 21, the portion 21 nesting within the side walls 15 of the back which forms a concealment 35 therefor when the device is folded into its chair position and gives the back a unitary appearance. A hinge 22 connects the back members 20 and 21 at their upper ends so that the back member 21 may also be rotated in a vertical 40 plane to have one end abut against the adjacent end of section 20, and to extend horizontally therewith.

A head board 23 may be provided, which extends perpendicularly from the back section 21. 45 When section 21 is closed against section 20 the head board extends slightly beyond the end of the side wall 15, and a mattress or the like which may be laid on the open back, may be retained thereby when the back is closed. Stretched over the inner faces of the portions 20 and 21 may be a covering of canvas or other like material, as at 24. Or, if desired, this may take the form of a suitable spring so that when the back portions 50 55

are unfolded they will afford a firm yet yielding support as a bed.

It will thus be seen that with my improved construction a strong, rigid and compact bed 5 may be combined with a convertible arm chair, each retaining its respective functions to the fullest extent. I preferably form my base 10 of a box-like construction, that is, a considerable portion of its depth is enclosed on four sides 10 so as to form a compartment therein which may be used for the storage of bedding, mattress, pillows, etc.

It will readily be seen that various changes may be made in the details of my construction and the arrangement of the parts thereof without departing from the spirit of my invention, and I therefore do not intend to be restricted thereto except as set forth in the following claim.

I claim as my invention:

20 In a convertible chair of the class described, an upwardly open hollow base portion, a seat hinged to said base at the forward edge thereof and being adapted to be turned on said hinge in a vertical plane and adapted to extend horizontally from 25 said base portion, side arm rests extending from

said seat and provided with a horizontally extending portion at their rearward ends and adapted to support said seat in its horizontally extended position, a back rest hinged adjacent its lower end to said base and normally abutting thereon and having a cushion extending forwardly from the plane thereof, the said back rest being adapted to be turned about its said hinge as a pivot in a vertical plane and to rest horizontally on the base portion with the said 10 cushion nesting within the hollow thereof, side 10 walls formed on said back rest and extending rearwardly therefrom and coextensive therewith, an extensible bed portion hinged to the top of said back rest and normally adapted to be carried thereby and to lie against it nested within said 15 side walls, a fixed head board extending from the lower end of said bed portion adapted to extend over the lower end of said back rest to normally provide a retaining end closure, said 20 extensible bed portion being adapted to pivot about its hinge and to lie extended in a horizontal position on said extended seat and to be supported thereby.

AXEL LANQUIST.
